(57) **CLAIM**

The ornamental design for a vehicle body exterior, as shown and described.

DESCRIPTION

FIG. 1 is a front view of a vehicle body exterior;
FIG. 2 is a front and left side perspective view thereof;
FIG. 3 is a left side elevation view thereof;
FIG. 4 is a top plan view thereof;
FIG. 5 is rear and left side perspective view thereof; and,
FIG. 6 is a rear elevation view thereof.
The broken lines shown in the drawings illustrate portions of the vehicle body exterior that form no part of the claimed design.
